US0D1030319S

(12) **United States Design Patent** (10) **Patent No.:** **US D1,030,319 S**
(45) **Date of Patent:** **** Jun. 11, 2024**

(54) **PROTECTIVE CASE FOR WIRELESS
EARPHONE**

(71) Applicant: **Yehu Lu**, Chaohu (CN)

(72) Inventor: **Yehu Lu**, Chaohu (CN)

(**) Term: **15 Years**

(21) Appl. No.: **29/864,592**

(22) Filed: **Jun. 6, 2022**

(30) **Foreign Application Priority Data**

Dec. 10, 2021 (CN) 202130820756.1

(51) **LOC (14) Cl.** **03-01**

(52) **U.S. Cl.**

(57) **CLAIM**

The ornamental design for a protective case for wireless earphone, as shown and described.

DESCRIPTION

FIG. 1 is a perspective view of a protective case for wireless earphone showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the protective case for wireless earphone where the protective case for wireless earphone is in a configuration of use.

The broken lines in the drawings depict portions of the protective case for wireless earphone that form no part of the claimed design.

1 Claim, 9 Drawing Sheets
